E. F. Hendroth
Attorney

UNITED STATES PATENT OFFICE

2,571,921

ATOMIZER OF SINGLE PIECE
CONSTRUCTION

Robert Morris, Flushing, N. Y.

Application June 2, 1948, Serial No. 30,531

2 Claims. (Cl. 299—90)

1

This invention relates to atomizers and more particularly to atomizers used with flexible containers.

An object of this invention is to provide an atomizing or spray head unit which is inserted in a flexible container and wherein the spraying device is a single complete unit which is one part and self contained.

Another object is to provide an atomizer wherein, having a flexible container, air contained in the unit is utilized for atomizing the liquid by pressure of the sides of the container.

A further object of this invention is to provide a one part spray head unit whereby any container using the same is easy to apply and handy to use with one hand only.

An additional object of this invention is to provide an atomizer wherein the atomizing head unit is inserted in a container under pressure thus reducing possibility of adulteration of the contents by removal of the head unit.

Other objects and purposes of the invention will be apparent from the following detailed description of one preferred embodiment thereof when taken with the drawings in which:

Fig. 1 is a sectional view taken through an atomizer head unit as applied to a medicament or liquid container.

Fig. 2 is a partial sectional view taken on the line 2—2 of Fig. 1, and

Fig. 3 is a side elevational view of the atomizer, parts thereof being broken away for clarity.

In the drawings the same reference characters are used to indicate similar parts.

As will be seen by referring to the drawings, a container 1 is provided and which is constructed of a flexible material such as a plastic or other suitable substance which will be unaffected by medicaments contained therein. The container 1 has a thickened neck portion 2 on the outside of which may be arranged screw threads 3 for the purpose of threading thereon a closure member, not shown, to insure no leakage from the container and also for sanitary reasons.

In the container there is a medicament or other liquid of any desired type to be sprayed, designated as 4.

The mouth 5 of the container may if desired be shaped with inwardly sloping side walls as shown in the drawings but this is a matter of choice.

Inserted in the mouth 5 is an atomizing or spraying head unit 6 having a flange 7 formed thereon which abuts against the top of the container at the mouth 5. This unit 6 may also be

2

made without a flange 7 and the container so constructed that the base of atomizing unit 6 will be abutted on the inside of thickened neck portion 2. The head unit 6 may be provided with flared sides 8 in order to insure a tight fit when pressed into the mouth 5 of the container. The spraying head unit 6 is constructed as a single piece preferably formed by molding from a plastic or other suitable substance which will be unaffected by medicaments contained therein. Centrally of the unit 6 on the interior thereof is a circular depending portion 9. Between the sides 8 and the depending portion 9 the head unit 6 is hollow for providing greater air volume in the container 1.

Extending substantially through the portion 9 is a longitudinal central bore 10 terminating in a shoulder 11. Above the bore 10 is an annular chamber 12 of smaller diameter than the bore 10 and above the chamber 12 is a mixing chamber 13 of smaller diameter than the chamber 12. The bore 10 and the two chambers 12 and 13 form in effect a stepped down series of bores in the unit head 6 as shown in the drawings. An opening 14 connects the mixing chamber 13 with the atmosphere and forms the outlet for the atomized medicament or liquid. In the bore 10 are grooves 15 on diametrically opposite sides which extend along the side of the bore 10, opening into the annular chamber 12 and through chamber 12 into the mixing chamber 13 as shown in Figs. 1 and 2.

Inserted in the bore 10 is a tube 16 of any suitable material which is impervious to the medicament or liquid in the container 1. The upper end of tube 16 abuts against the shoulder 11 and extends down into the container 1 and rests on or is in close proximity to the bottom thereof. As is shown in Fig. 1, the grooves 15 extend beyond the upper end of the tube 16 for a purpose to be later described.

Having now described the construction of the present device, it is deemed desirable to set forth the method of operation thereof.

The tube 16 is pressed into the bore 10 until it abuts the shoulder 11. The container 1 is then partially filled with a medicament or other liquid material 4 which it is desired to atomize or spray. The entire spraying head unit 6 together with the tube 16 is inserted in the mouth 5 of the container 1 and pressed therein until the flange 7 abuts against the top of the container. The tube 16 will then extend into the liquid 4. Now the entire unit is assembled and when the flexible sides 8 of the container 1 are pressed into a position sim-

ilar to that shown in dotted lines in Fig. 3, liquid will be forced up through the tube 16 into the chamber 12. At the same time air inside the container will be forced up through grooves 15 into chamber 12 and the liquid and air together will enter into mixing chamber 13. In chamber 13 the liquid and air will thoroughly mix and pass out through opening 14 as a fine spray.

The operation of the device is therefore simple and may easily be accomplished by using only one hand. The construction of the atomizer is simple, sturdy, and inexpensive to manufacture. It is understood that although a single preferred embodiment of the invention has been described for purposes of illustration that changes and modifications may be introduced with regard to certain details of construction and shape of the atomizer, without departing from the basic principles of the invention.

I claim:

1. An atomizer comprising a flexible container adapted to hold a liquid and having an opening therein, a single piece elastic atomizing head unit inserted in said opening, said head unit having a central circular depending portion thereon, a tube inserted in a central bore in said depending portion of said head unit and extending into liquid contained in said container, diametrically opposed grooves in said depending portion of said head unit contiguous with said tube in said central bore, a cylindrical chamber in said head unit above said tube, said tube opening into said cylindrical chamber, a mixing chamber in said head unit above said cylindrical chamber and emerging therefrom, said grooves in said unit extending from the lower extremity thereof to said cylindrical chamber opening thereinto and through said chamber opening into said mixing chamber, and said head unit having a spray outlet therein connected to said mixing chamber whereby upon squeezing said container liquid will flow through said tube and be mixed with air flowing through said grooves and the atomized

mixture will be forced from said spray outlet as a fine spray.

2. An atomizer comprising a flexible container adapted to hold a liquid and having an opening therein, a single piece elastic atomizing head unit inserted in said opening, a spray outlet in said head unit, a mixing chamber in said head unit communicating with said spray outlet, a cylindrical chamber in said head of larger diameter than said mixing chamber and communicating therewith, a central depending portion in said head unit having a central longitudinal bore therein, said bore opening into said cylindrical chamber, diametrically opposed grooves in said head unit adjacent said bore and opening into said cylindrical chamber at one end thereof and extending along said bore into said container, a tube in said bore communicating with said cylindrical chamber and extending into liquid in said container whereby liquid and air may be forced from said container to said mixing chamber and the atomized mixture forced from said spray outlet.
